United States Patent Office

Des. 205,165
Patented June 28, 1966

205,165

TRANSMISSION UNIT OR SIMILAR ARTICLE

Don Heyer, 1019 N. Raynold, Fullerton, Calif.

Filed Oct. 19, 1965, Ser. No. 87,592

Term of patent 14 years

(Cl. D55—1)

FIG. 1.

FIG. 2.

FIG. 3.

FIG. 4.

FIG. 1 is a front perspective view of a transmission unit or similar article showing my new design;

FIG. 2 is a rear perspective view thereof;

FIG. 3 is a front perspective view thereof in an alternate position; and

FIG. 4 is a rear perspective view thereof as shown in FIG. 3.

I claim:

The ornamental design for a transmission unit or similar article, as shown.
